UNITED STATES PATENT OFFICE.

CHARLES B. HEADLY AND JOHN S. CARROW, OF PHILADELPHIA,
PENNSYLVANIA.

PROCESS OF MOUNTING METALLIC ORNAMENTS UPON GLASS, &c.

SPECIFICATION forming part of Letters Patent No. 479,743, dated July 26, 1892.

Application filed February 13, 1892. Serial No. 421,459. (No specimens.)

To all whom it may concern:

Be it known that we, CHARLES B. HEADLY and JOHN S. CARROW, citizens of the United States, and residents of Philadelphia, Pennsylvania, have invented an Improved Process of Mounting Metallic Ornaments upon Glass and Similar Ware, of which the following is a specification.

The object of our invention is to so mount metallic open-work upon glass and similar material in such a manner that after the article has been plated the solder joints are not exposed, but are plated similar to the body of the material. This object we attain in the following manner, reference being had to the accompanying drawings, which illustrate the different steps in the process, and in which—

Figure 1 is a view of one form of ornamentation as it is cast ready to be shaped to the form of the article. Fig. 2 is a side view of a glassbottle to which the ornamentation shown in Fig. 1 is to be applied. Fig. 3 is a view showing the ornamentation partially applied to the bottle. Fig. 4 is a view showing the ornamentation removed from the bottle, but shaped to conform to the body thereof, and ready to be immersed in the whitening-bath. Fig. 5 is a view showing the ornamentation again applied to the bottle and the upper edges soldered together, so that it cannot be removed therefrom; and Fig. 6 is a view showing the bottle with the ornamentation immersed in an electroplating solution.

It will be understood that similar material to glass can be used without departing from our invention, the word "similar" in this instance meaning any material which can be immersed in an electroplating solution without taking the electroplating, and it will also be understood that the design shown in the accompanying drawings need not be adhered to in carrying out our invention, and that the shape of the article upon which the ornamentation is mounted is immaterial.

The first step in the process is to mold the open-work ornamentation. This is done by producing a flat mold of the design required, and the sections *a* can be made singly or in pairs or cast in a single piece, as desired. The material preferably used is white-metal, which is sufficiently pliable to enable the

manufacturer to bend it and shape it to the article. The design in most instances where a large number of the same article are to be made is made for that one article; but where a small number of a certain article is to be made the open-work ornamentation may be cut from a large casting.

The operator mounts upon the bottle *B* (shown in Fig. 2) the ornamentation shown in Fig. 1, soldering the two edges of the ornamentation together at *bb*, and when the ornamentation extends under the bottle, as is the case of the design shown in the drawings, the operator turns the extensions *d* under the bottle and solders them together, as will be clearly understood by referring to Fig. 1. The extensions *e*, however, are preferably left, as shown in Fig. 3, so that the ornamentation after being soldered can be removed from the article, as shown in Fig. 4. It is then dipped into a quick-acting plating solution, and when silver-plating is applied the entire structure is coated. It is then removed from the electroplating-bath, and the white coat on the outer portion of the open-work is then removed by burnishing. The article is then prepared for the final electroplating-bath, thus leaving the white coating only at the back, as in most cases where glass is used the back of the ornamentation can be seen through the glass. The plating covers up or removes any dark spots on the back of the ornamentation which would otherwise show through the glass and spoil the appearance of the article.

The next step in the process is to mount the ornamentation upon the bottle, turning down the edges *c*, as shown in Fig. 5, and securing them together by solder joints at *f*, as indicated in Fig. 1, thus securely fastening the ornamentation upon the bottle.

The next step in the process is to immerse the bottle or other article, with the ornamentation secured thereto, in the electroplating solution, as shown in Fig. 6, preferably a slow-acting solution, so as to thoroughly plate all of the ornamentation, including the solder joints. The article is then removed from the solution and thoroughly cleaned and polished, ready to be placed upon the market.

Thus by our improvement we are enabled

to manufacture articles of the character described at a comparatively small cost, and the solder joints will be plated and will have the same appearance as the body of the ornamentation.

5 In some instances when opaque glassware or similar material is used the whitening step in the process may be dispensed with.

When large numbers of the same article 10 are to be mounted with the same ornamentation, a dummy or former can be used to shape the ornamentation in the first place without departing from our invention. The ornamentation, however, is finally secured to the article for which it is intended.

15 We claim as our invention—

1. The within-described process of ornamenting glassware or similar material, said process consisting in casting the metallic 20 open-work ornamental design, fitting it to the article to be ornamented, soldering it together at the joints, subjecting it to an electroplating solution, which will plate the metallic ornamentation and the solder joints without 25 plating the article, substantially as set forth.

2. The within-described process of ornamenting glassware or similar material, said process consisting in casting the metallic 30 open-work ornamental design, fitting it to the article to be ornamented in such a manner that it can be withdrawn from the article, sol-

dering it together at the joints, removing it from the article, subjecting it to a plating solution in order to plate the back of the ornamentation, mounting it again upon the article, turning down and fitting and soldering together the remaining portion of the ornamentation so as to confine it to the article, and finally immersing the article, with the ornamentation, in an electroplating solution which 35 will plate the metallic ornamentation without plating the article, substantially as specified.

3. The process herein described of ornamenting glassware or similar material, said process consisting in first casting a design in 40 white-metal and having tapered portions to fit over a shoulder, mounting said ornamentation upon a form, securing the edges together by solder, immersing the article, with the ornamentation, in an electroplating-bath, 45 whereby the ornamentation and soldered joints are plated without plating the article, substantially as specified.

In testimony whereof we have signed our names to this specification in the presence of 50 two subscribing witnesses.
